(57) **CLAIM**

The ornamental design for a putter sole, as shown and described.

DESCRIPTION

FIG. 1 is a front perspective view of the putter sole.

FIG. 2 is a front view of the putter sole.

FIG. 3 is a right-side view of the putter sole.

FIG. 4 is a left-side view of the putter sole.

FIG. 5 is a back view of the putter sole.

FIG. 6 is a top view of the putter sole.

FIG. 7 is a bottom view of the putter sole; and,

FIG. 8 is a rear perspective view of the putter sole.

The broken line showing on the drawing views is included for the purpose of illustrating and forms no part of the claimed design.

1 Claim, 3 Drawing Sheets

FIG. 2

FIG. 3

FIG. 4

FIG. 5

FIG. 6

FIG. 7
